UNITED STATES PATENT OFFICE.

UBERT K. HALL, OF PORTLAND, OREGON.

DESK-BASKET.

No. 921,694.

Specification of Letters Patent. Patented May 18, 1909.

Application filed February 7, 1908. Serial No. 414,767.

To all whom it may concern:

Be it known that I, UBERT K. HALL, a citizen of the United States, residing in the city of Portland, county of Multnomah, and State of Oregon, have invented certain new and useful Improvements in Desk-Baskets, of which the following is a specification.

My invention relates to desk baskets and particularly to that class of desk baskets called "nest" baskets, comprising two or more baskets for receiving letters, papers, and the like, mounted one above the other in order to save desk space.

I am aware that "nest" baskets with the several baskets rigidly and permanently joined together are in common use. However, in removing letters and papers from the under baskets of a series of baskets permanently secured together, these papers and letters are frequently crumpled and torn by engagement with the supporting legs or members connecting the different baskets.

The principal object of my invention is to provide a basket of the character referred to in which the different baskets, mounted one above the other, can be readily moved relatively to each other to make more easy the removal of papers from a lower basket.

My invention will be readily understood from the following description, reference being had to the accompanying drawings, in which—

Figure 1 is a perspective view of a three story basket in the rest position; Fig. 2 is a similar view of the same basket but showing how the upper baskets can be raised to permit removal of papers from the under basket; Fig. 3 is a side elevation of a modified form of my invention; in which the baskets are moved or turned laterally instead of vertically; Fig. 4 is a plan view on line A—B of Fig. 3.

Referring to the drawings, 1, 2 and 3 designate three baskets supported one above the other by means of the supporting legs or members 4—4 and 5—5. In this embodiment of the invention the supporting legs or members 4—4, are provided with a hinge joint 6 whereby the upper baskets 1 and 2 can be raised, as shown in Fig. 2, to permit the removal of papers from basket 3. Basket 1, it will be understood can be raised from basket 2 to permit the removal of papers from the latter. The supporting legs 5—5 are provided with feet or rest hooks 7 which rest upon the basket next beneath. The

supporting legs 4—4 are preferably set in some little distance from the outer edges of the baskets so as to provide guards to prevent the letters or papers from slipping out rearwardly.

In Figs. 3 and 4, a modified form of the invention is shown in which the baskets are hinged one above the other upon a standard 8, in such manner that each basket can be turned upon a vertical axis independently of the others and thus permit the removal of letters and papers from the under basket without interference from the next basket above.

In practical use, letters and papers are put into these baskets one at a time and lie in the basket in all sorts of positions. They are usually removed all together. It will be understood, therefore, that it is a very great convenience and saving of time to be able to move the basket or baskets next above the one from which the papers are to be taken so as to have free access to the basket from which you wish to take the papers. This is readily and quickly accomplished by my invention. In one case the separate baskets are lifted in a vertical plane, turning upon a horizontal axis; and in the other embodiment of the invention the baskets turn upon a vertical axis and are moved independently in a horizontal plane.

I am aware that modifications other than what I have shown can readily be made without departing from the spirit of my invention, and I do not therefore, limit my invention to the particular constructions shown in the drawings.

What I claim as my invention is—

1. A desk basket comprising a plurality of baskets or trays supported one above the other at a distance apart by means of supporting legs or extensions therebetween, each basket being supported by a hinge connection at one side thereof and free to be moved at the opposite side thereof, whereby it can be moved upon its hinge joint relatively to the other baskets, substantially as described.

2. A desk basket comprising a plurality of baskets or trays mounted one above the other at a distance apart by means of supporting legs or extensions, each basket being hinged at one side to a portion of said legs or extensions and movably supported by the others, whereby it can be moved upon its hinge connection relatively to the other baskets, substantially as described.

3. A desk basket comprising a plurality of baskets or trays, supporting legs or extensions between said baskets supporting them at a distance one above the other, the baskets being hinged at one side to supporting legs

wardly and rest freely upon the basket next beneath, whereby said upper baskets can be moved upon the hinge joint, substantially as described. 10
